CASSEROLE OR SIMILAR ARTICLE

Frank J. Benes, Lancaster, Ohio, assignor to Anchor Hocking Glass Corporation, Lancaster, Ohio, a corporation of Delaware

Original design application Dec. 6, 1966, Ser. No. 4,928. Divided and this application July 12, 1967, Ser. No. 8,194

Term of patent 14 years

(Cl. D44—15)

FIG. 1 is a perspective view of a casserole or similar article showing the design of the present invention;

FIG. 2 is an exploded view thereof;

FIG. 3 is a top view thereof;

FIG. 4 is a side view thereof;

FIG. 5 is a sectional view taken along line 5—5 of FIG. 3;

FIG. 6 is a sectional view taken along 6—6 of FIG. 4.

The characteristic features of the design reside in the combination of a casserole having downwardly curved handles and an upper body portion of slight taper and a lower body portion of greater taper, and a cover having the configuration shown and bearing handles which are curved in the opposite direction from those of the body.

The present application is a division of my copending design application Ser. No. 4,928, filed Dec. 6, 1966.

I claim:

The ornamental design for a casserole or similar article, substantially as shown and described.
